UNITED STATES PATENT OFFICE.

HECTOR DE NOLLY, OF LYON, FRANCE, ASSIGNOR TO LA SOCIETE METALLURGIQUE
DU FRAYOL, OF LYON, FRANCE.

ELECTRIC FURNACE.

1,417,303.

Specification of Letters Patent. Patented May 23, 1922.

Application filed April 8, 1920. Serial No. 372,176.

To all whom it may concern:

Be it known that I, HECTOR DE NOLLY, a citizen of the French Republic, of Lyon, France, have invented certain new and useful

5 Improvements in Electric Furnaces, (for which I have filed applications in France, January 7, 1920; Belgium, January 10, 1920; Italy, January 9, 1920; Spain, January 16, 1920; Germany, February 5, 1920; Austria, 10 February 17, 1920,) of which the following is a specification.

The present invention relates to electric furnaces for the fusion and refining of metals and other substances.

15 In the furnace the usual roofing or vaulting constructed of silica is replaced by a block of graphite, the height of which can be regulated, said block being constituted by an assemblage of several pieces of suitable 20 shape and size. The upper part of the furnace is provided with a cooling jacket constructed of cast iron or moulded steel and through which water circulates. Within this jacket the block of graphite can slide 25 vertically.

This construction allows the capacity of the working chamber to be varied by raising or lowering the block. Or by removing the block the furnace can be completely 30 open at its upper part, if required.

Further, the invention provides an un-wearable vaulting or one that can easily be replaced during working of the furnace, as the silica vaulting usually employed rapidly 35 becomes useless owing to radiation from the arc, and more particularly to the volatilization of lime, which is unavoidable when ultra basic slag as is generally the case is treated.

Further, a tightworking chamber is obtained 40 since in the improved furnace the electrodes do not pass through the vaulting; consequently a reduced atmosphere can be maintained and oxidation of the bath becomes impossible. The block of graphite 45 forming the vaulting not having to be continually manipulated to regulate the voltage, a tight joint can be formed by means of clay or other refractory product, packed between the block and the cooling jacket immediately 50 the furnace is working normally.

The furnace also comprises further features, notably the position and arrangement of movable electrodes and the employment of lateral conductive plates connected in part 55 allel with a conductive plate provided at the

bottom of the furnace. These means allow of easy priming starting from a cold charge. As long as the lining of the furnace is not sufficiently hot to be conductive, the return of the current is effected through the lateral 60 conductive plates. For this purpose when being charged the furnace is slightly inclined in such a way that the charge is in contact with the lateral conductive plates. In accordance with the fusion of the substances 65 the sole is heated and when it is sufficiently conductive, the return current operates through the conductive plate at the bottom of the furnace and it is sufficient then to tilt the furnace in the reverse direction so that 70 the lateral conductive plates emerge from the bath.

It is to be observed that with such arrangement, it is very easy to vary the electric working of the furnace during operation 75 since by simple tilting of the furnace to the right or left, the whole or a part of the current can be caused to pass through the metallic bath or the slag.

The furnace may be worked by monophase 80 or triphase currents, the phase displacement found in triphase current being so feeble that it is not industrially harmful.

The annexed drawing shows an example 85 of construction of the furnace.

Fig. 1 is a longitudinal section on line 1—1 of Fig. 2, of the left side only of the furnace.

Fig. 2 is a transverse section on line 2—2 of Fig. 1.

The two round current conducting electrodes *a* pass into the furnace through the end walls of the body of the furnace. These electrodes are cooled by water circulating jackets *b*. The electric connections of these 95 electrodes is obtained by means of collars *c* constructed to allow if necessary the rotation of the electrodes round their axes. The voltage is maintained constant by means of small motors *d* governing the movement of 100 the supporting carriages *e* of the electrodes by means of screws rods and nuts. Guiding rollers *f* support the electrodes and reduce to the minimum the friction of the electrodes on the cooling jackets *b*.

In monophase working the furnace comprises two movable electrodes which are connected in parallel to one of the feeders, the other feeder being connected to the conductive plate at the bottom of the furnace which 110

is itself connected in parallel with the two lateral conductive plates.

In triphase working the furnace comprises two movable electrodes each of which is connected to a separate feeder, the third feeder being connected to the conductive plate at the bottom of the furnace, which is connected in parallel with the two lateral conductive plates.

10 The supports and trackways *g* are fixed to the supporting framework of the furnace by means of bolts insulated by means of micanite, asbestos or any other insulating material.

15 The water circulation collars *b* serving for cooling the electrodes are also insulated.

The conductive plate *h* at the bottom of the furnace, as well as the two lateral conductive plates *i* do not require special insulation, the refractory substances being sufficiently resistant; it is sufficient to make the openings in the iron casing of the furnace a little larger than the section of the connecting heads of these plates.

20 25 The connections of the conductive plate *h* are shown at *j* and comprise supple cables to allow the oscillations of the furnace. Rigid conductors *i'* are used, however, to connect electrodes *i* in parallel with the conductive plate *h* as shown in Fig 2.

25 30 The conductors *k* and *l* conveying the current to the electrodes *a* comprise rigid parts and supple parts to allow the oscillations of the furnace and to allow the maximum movement of the electrodes *a*.

35 The furnace can oscillate on a cradle *m* having curved ends carrying toothed sectors *n* supported by rollers working on fixed axles *o*. An electric motor *p* effects the oscillating or rocking movements of the furnace.

40 45 The blocks *q* and *r* forming the vaulting are cooled by water circulating jackets *s* and are suspended by a steel cable *t* by means of a fixed pulley and an intermediate pulley, the cable being operated by means of a winch fixed on the wall of the furnace.

50 55 A safety chain *u* fixed by a hook to the cross bar *v* with a certain play so as not to paralyze the downward movement of the blocks *q* *r* forming the vaulting prevents any accident in case of rupture of the steel cable. When these blocks are to be replaced the chains of an electric travelling crane are hooked to two rings which the movable cross bar *v* carries. The bar *v* is tilted slightly by the crane so as to stretch the safety chain in order to allow of unhooking the attachment of the steel cable, and it is then sufficient to execute the replacement by means of the electric crane. Under these conditions the change of blocks is effected very rapidly.

60 65 For furnaces of large capacity the vault forming blocks are sub-divided into several

groups to facilitate operation, each of these groups can be changed separately. Also each group having its operating tackle, the regulation of the height is obtained without difficulty in case of unequal wear.

70 What I claim as my invention and desire to secure by Letters Patent of the United States is:—

1. An electric furnace comprising a body of refractory material open at its upper part, a block of graphite vertically movable in said open upper part and fitting therein so as to form a vaulting and forming with said body the reduction chamber of the furnace, means for effecting the movement of said block, inclined movable electrodes passing through the side walls of said body, means for imparting movement to said electrodes, a polar plate at the bottom of said reduction chamber, lateral polar plates mounted in parallel with said bottom polar plate and extending into said reduction chamber, means for conveying electric current to said polar plates and to said electrodes, means supporting said body and means whereby said body can be rocked upon said supporting means.

2. An electric furnace comprising a body of refractory material open at its upper part, a block of graphite vertically movable in said open upper part and fitting therein so as to form a vaulting, and forming with said body the reduction chamber of the furnace, pulley mechanism for lifting or lowering said block, means for cooling said block, inclined movable electrodes passing through the side walls of said body, means for cooling said electrodes, collars surrounding said electrodes, carriages connected to said collars, rails supporting said carriages, means for moving said carriages on said rails and thereby said electrodes, a polar plate at the bottom of said reduction chamber, lateral polar plates mounted in parallel with said bottom polar plate and extending into said reduction chamber, means for conveying electric current to said polar plates and to said electrodes, means supporting said body and means whereby said body can be rocked upon said supporting means.

3. An electric furnace comprising a body of refractory material open at its upper part, a block of graphite vertically movable in said open upper part and fitting therein so as to form a vaulting, and forming with said body the reduction chamber of the furnace, pulley mechanism for lifting or lowering said block, means for cooling said block, inclined movable electrodes passing through the side walls of said body, means for cooling said electrodes, collars surrounding said electrodes, carriages connected to said collars, rails supporting said carriages, means for moving said carriages on said

rails and thereby said electrodes, a polar plate at the bottom of said reduction chamber, lateral polar plates mounted in parallel with said bottom polar plate and extending 5 into said reduction chamber, means for conveying electric current to said polar plates and to said electrodes, a cradle supporting said body, curved racks carried by said cradle, toothed wheels gearing with said 10 cradles, a shaft carrying said toothed wheels, a base carrying said shaft and means for

imparting rotation to said shaft to rock said body on said base through said toothed wheels and curved racks.

In witness whereof I have signed this specification in the presence of two wit- 15 nesses.

HECTOR DE NOLLY.
